ACTION GAME BOARD

George L. Bell, 230 Center St., Huron, Ohio
Filed July 18, 1961, Ser. No. 124,829
1 Claim. (Cl. 273—123)

This invention relates to an action game for two, four or six players, and more particularly to a board upon which an action game called "Bank Ball" can be played.

A variety of games are presently played on game boards in which game pieces in the form of discs are propelled across the board by snapping with the fingers, tilting the board, or by striking the discs with paddles and the like. The discs may strike one another as in billiards, or they may be directed into goals in the form of holes or wickets. The participants in such games take turns, and when one player is moving the game piece the other players customarily remain idle while observing the progress of the game. In other games a pair of participants may attempt to move the game pieces and simultaneously defend a certain goal, but in such games the number of players is limited to two or four persons.

It is, therefore, an object of the present invention to provide an action game requiring constant player activity which may be played by young or old persons.

Another object of the invention is to provide a board for an action game which may be played by two, four or six players that actively participate in the game at all times.

Other objects of the invention will be apparent from the following specifications and from the drawings in which like numbers are used throughout to identify like parts.

FIG. 1 is a plan view of the game board of the present invention;

FIG. 2 is a vertical sectional view taken along the line 2—2 of FIG. 1; and

FIG. 3 is a side elevation view of the action game board.

In order to achieve the above objects of the invention, there is provided a game board for an action game that has a frame which extends around a playing surface and extends upwardly therefrom. The game board also has a rail that is spaced upwardly from the playing surface for defining a court in the central portion of the board. A portion of the board between the rail and the frame is marked to divide the playing surface outside the court into a plurality of shooting zones from which discs are propelled into the court by snapping them with the fingers to slide along the playing surface and strike a rubber ball to impel it towards one of a pair of opposed goals in the court. The ball remains in the court, rebounding off of the rail until it finally rolls into one of the goals while the discs are free to slide under the rail into one of the shooting zones.

Referring now to the drawings, there is shown in FIGS. 1 to 3 an action game board 10 constructed in accordance with the present invention and which may be of any rigid material such as wood, metal and cardboard or the like. The game board 10 is preferably rectangular and of sufficient size to enable two, four, or six participants to play the game simultaneously. A rectangular game board 10 measuring approximately two feet by three feet has been found large enough for six players yet small enough to be easily transported.

The game board 10 includes a rectangular base 11 in the form of a planar sheet having a smooth, flat upper surface 12 which constitutes the playing surface of the game. A frame 13 extends around the peripheral edge of the base 11 and protrudes upwardly from the playing surface 12. The frame 13 gives rigidity to the game board

2

10 and defines the perimeter of the playing surface 12.

A continuous rail 14 defines a generally rectangular court in the center portion of the playing surface 12 that is located inwardly from the frame 13. The rail 14 is rigid and is spaced upwardly from the playing surface 12 by a plurality of posts 15 which support the rail 14.

A pair of spaced openings 16 and 17 form goals at the opposite ends of the court defined by the rail 14. The openings 16 and 17 are located along the longitudinal center line of the game board 10 adjacent opposed end sections of the rail 14, and these openings are preferably circular with relatively large diameters. The game is played with a resilient ball 18 that is free to roll along the playing surface 12 in the court defined by the rail 14 and to rebound from this rail. The ball 18 may be of any diameter although it must be large enough to prevent its passage beneath the rail 14 yet be small enough to roll in the goal forming openings 16 and 17.

Game pieces 19 in the form of discs, such as checkers, are snapped by the fingers and slide along the playing surface 12 to strike the ball 18 thereby impelling it toward one of the openings 16 and 17. The discs 19 are retained on the playing surface 12 by the upwardly extending portion of the frame 13.

Markings 20, 21, 22, 23, 24 and 25 on a portion of the playing surface 12 between the frame 13 and the rail 14 define shooting zones on the game board 10 from which the discs 19 are snapped into the court surrounded by the rail 14. The markings 20 and 23 extend along the transverse center line of the game board 10 normal to the frame 13 to divide the marginal portion of the game board 10 into two shooting zones of equal size, and the diagonal markings 21, 22, 24 and 25 are disregarded when only two players are participating in the game.

When four players are participating they are divided into two teams, and one player has a shooting zone between the markings 20 and 22 while his partner on the same team has a shooting zone between the markings 21 and 23. The two players on the opposing team have shooting zones between the markings 23 and 25 as well as 24 and 20. It is apparent that in the case of four players, the shooting zones overlap between the diagonal markings 21, 22 and 24, 25. When more than two players participate, the discs 19 may be passed freely between the team members upon request.

When six players participate, two teams of three players each are formed with two players of a team playing forward positions opposite each other in the zones marked by lines 20, 21 and 22, 23. The third member plays defensively in the zone marked by lines 24, 25 at the opposite end of the board. This team with two forwards and one defensive member attempts to place the ball in opening 16. The opposing team follows the same pattern with two members playing forward positions opposite each other in the zones marked by the lines 23, 24, and 20, 25, and the defensive member plays in the zone marked by the lines 21, 22.

At the start of play each player is given one game piece 19 who positions it within his shooting zone as shown in FIG. 1 which illustrates the positioning of the game pieces 19 for the start of a game when six players are participating. The resilient ball 18 is placed in a detent 26 that is located within a circle 27 on the playing surface 12 at the center of the court enclosed by the rail 14.

The detent 26 has a diameter considerably smaller than the diameter of the ball 18 whereby the detent 26 merely positions the ball 18 in the center marking circle 27, and the ball 18 is readily moved out of this detent by striking it with a disc 19. It will be apparent that at the start of the game each player will have one disc 19 in his respective shooting zone.

At a pre-arranged signal such as a count of three, one player on each team snaps his disc 19 to propel it from his respective shooting zone into the court defined by the rail 14. The initial shot is made by only two players, and when four or six players participate, only two may make this first shot. The initial shot may be made from any zone, except when two play, and then the shot must be made from the zones marked by the lines 21, 22 and 24, 25. After the ball is placed in motion by the initial shot all players may shoot from their proper zones.

An important feature of the invention is that the posts 15 space the rail 14 upwardly from the playing surface 12 a distance greater than the thickness of each disc 19 to enable the disc to slide over the playing surface 12 and beneath the rail 14 into and out of the central court. As soon as any disc enters the central court by passing under the rail 14 it is considered to be in free play and may be grasped by an opposing player. However, when any disc leaves the central court into a shooting zone no player from an opposing team may reach into the shooting zone to grasp the disc, and if such an event occurs it is considered to be a "foul." A foul also occurs if any player touches the ball 18 or if any player impels the ball 18 with such force that it leaves the court.

In the case of a "foul," the ball 18 is placed in one of a pair of detents 28 and 29 positioned between the detent 26 and the openings 16 and 17 respectively. If a foul is called against a player who is attempting to impel the ball 18 into the opening 16, the ball 18 is placed in the detent 29 and the player attempts to impel the ball toward the goal 16 by propelling a disc 19 from his shooting zone without interference from the opposing player or players. When a team is given the privilege of making a foul shot any member of the team may be selected to make the shot.

Before taking his "free" shot, the selected player declares how many times the ball 18 is to bank off the rail 14 before it is considered to be in free play. After this number of banks, the ball 18 is then free and may be impelled in any direction by the discs 19 that are snapped from any of the shooting zones in a manner previously described. When the ball does not complete all the banks and fails to drop into the opening it must be allowed to stop before the game is resumed.

While the preferred embodiment of the invention has

been disclosed and described, it will be apparent that various modifications may be made to this action game board without departing from the spirit of the invention or the scope of the subjoined claim. For example, suitable legs may be placed on the game board 10 to raise it from a supporting surface.

I claim.

An action game comprising a game board having a flat, rectangular playing surface, an edge frame extending 10 around the margins of said playing surface and protruding upwardly therefrom, a continuous rail, means for 15 mounting said rail in spaced relationship upwardly from said edge frame and parallel thereto and spaced vertically above said playing surface for defining a rectangular court in the central portion of said board and a passage 20 beneath said rail, markings on a marginal surface portion of said board between said rail and said edge frame for dividing said marginal surface portion into at least a single zone at each end thereof and a plurality of zones 25 at each side thereof, said playing surface having openings therein near opposed ends of said court for defining goals, and three ball retaining depressions in said playing surface, said depressions being located substantially in longitudinal alignment and at the two quarter points 30 and the center of said playing surface, a resilient ball for rolling on said playing surface within said court, said ball having a diameter greater than the vertical height of the passage between said rail and said surface and so related to the diameter of each of said openings 35 that said ball may drop into said openings, and a plurality of discs for sliding on said playing surface and striking said ball to impel the same toward said goals, each of said discs having a thickness less than the vertical spacing between said playing surface and said rail whereby 40 said discs may be propelled under said rail from any of said zones into said court for striking said ball and under said rail out of said court into another of said zones for contacting said frame.
